FIG. 1

FIG. 2

Des. 174,788

PAGE 2

FIG. 3

FIG. 4

To all whom it may concern:

Be it known that we, Homer D. Witzel and Glenn W. Rohweder, citizens of the United States, residing at Bettendorf, county of Scott, and State of Iowa, and Moline, county of Rock Island, and State of Illinois, have invented a new, original, and ornamental Design for an Operator's Station for a Crop Harvester, of which the following is a specification, reference being had to the accompanying drawings, forming a part hereof.

Figure 1 is a perspective view showing the front and right side of an operator's station for a crop harvester embodying our new design.

Figure 2 is a perspective view showing the left side of the operator's station.

Figure 3 is a perspective view showing the right side of the operator's station.

Figure 4 is a plan view of the operator's station.
Figure 5 is a perspective view of an environmental showing of the operator's station.

The depiction of the combine in phantom is for illustrative purposes only and is only one of several environments in which the operator's station may be used.

We claim:

The ornamental design for an operator's station for a crop harvester, substantially as shown and described.
